UNITED STATES PATENT OFFICE.

CLYDE J. COLEMAN, OF NEW ROCHELLE, NEW YORK, ASSIGNOR TO STERN-COLEMAN
DIAMOND MACHINE COMPANY, INC., OF NEW YORK, N. Y.

POLISHING-MACHINE.

1,313,260.

Specification of Letters Patent. Patented Aug. 19, 1919.

Application filed June 22, 1915. Serial No. 35,511.

To all whom it may concern:

Be it known that I, CLYDE J. COLEMAN, a citizen of the United States, and a resident of Premium Point Park, New Rochelle, county of Westchester, State of New York, have invented certain new and useful Improvements in Polishing-Machines, of which the following is a specification.

My invention relates to polishing machines and more particularly to machines for polishing gems or subjecting them to abrasive treatment.

The polishing of gems or precious stones requires great precision and the greatest skill has been required. The main object of the present invention is to provide an improved machine which is largely automatic, so that attendants with little skill in the art may by the use of the machine, polish gems with great accuracy and precision and in a minimum of time, and is also simple and efficient in operation and construction, permitting of easy adjustment of the stone in its various desired positions. The machine being automatic, one attendant may operate or watch several machines at a time, so that not only is highly skilled labor unnecessary, but one attendant may do the work heretofore required of several. The various novel features and combinations will more clearly appear from the following description and appended claims, taken in connection with the accompanying drawings.

In the drawings Figure 1 is a side view of a machine embodying my improvements in a preferred form. Fig. 2 is a plan view thereof. Fig. 3 is an end view thereof. Fig. 4 is a similar view, certain parts being broken away or shown in section to more clearly illustrate the operation. Fig. 5 is a section taken on the line 5—5 of Fig. 4. Fig. 6 is a section taken on the line 6—6 of Fig. 5. Fig. 7 is a section taken on the line 7—7 of Fig. 4. Fig. 8 is a partial view of the tripping mechanism similar to that of Fig. 4, but looking in the opposite direction. Fig. 9 is a detail end view of parts shown in Fig. 8. Fig. 10 is a longitudinal section of the dop and gem holder. Fig. 11 is a section taken on the line 11—11 of Fig. 10. Fig. 12 is an enlarged section taken on the line 12—12 of Fig. 2. Fig. 13 is a section taken on the line 13—13 of Fig. 12. Fig. 14 is a diagram illustrating the position of the gem with respect to the dop arc, and

Fig. 15 is a detail view showing the method of securing the stone to the arbor.

Referring to the drawings, 1 represents a suitable rotating polishing lap, carried by the spindle 2. The diamond or other precious stone 3 is secured in an arbor 4, by means of a suitable cement 3' or in any other suitable or well known manner. The cement is used in considerable body in the recess in the end of the arbor as shown in Fig. 15, a hole 4' being provided through which a pin or tool may be driven from the outside to loosen the cement and stone and dislodge them from the arbor after polishing all the facets on one side of the girdle. The arbor 4 is carried by a dop spindle 5 (see Fig. 10) in which it is slidably mounted along the axis of the arbor and the spindle, but is prevented from rotation therein by means of a key 6 (see also Fig. 11), so that the arbor may always be inserted in the dop in the same rotative position with respect thereto, whereby the stone will properly register with the index pointer 9, hereinafter referred to. The dop spindle 5 is rotatably mounted in a dop spindle 7, the spindle 5 having secured on its upper end a knurled hand nut 8, having an integral pointer 9, co-operating with a circular index scale 10 on the beveled upper edge of the dop spindle 7. Upon rotating the knurled nut 8, the spindle 5, together with the arbor 4 is rotated in the dop spindle 7, in order to bring the various facets of the diamond parallel with the polishing surface of the lap, in order that they may be polished. For the purpose of adjusting the arbor 4, together with the gem carried thereby, longitudinally along the axis of the dop spindle, the dop spindle has arranged centrally therein a rod 11 engaging a screw 12, integral or rigid with the arbor 4. At its upper end the rod 11 is provided with a rigid or integral screw-threaded portion 12', upon which is screwthreaded a small knurled nut 13 and a lock-nut 14. Upon turning the nut 13 relative to the dop spindle 7, the arbor 4, nut 8 and spindle 5, the rod 11 is turned relatively thereto, and operating upon the screw 12, causes the arbor 4 to be moved slowly longitudinally to the dop spindle 5. The dop spindle 7 has arranged integral or rigid therewith an extension 15, carrying an arcuate rack 16, slideable in an arcuate guide 17, in a carrying arm 18. In order to

adjust the axis of the dop and the gem with regard to the polishing surface, the arcuate rack 16 is moved in the arcuate guide 17, in various positions, in the well known manner. In order that this movement may be carefully regulated, the arm 18 contains a worm 19, operated by a thumb piece 20, the worm 19 engaging with the teeth of the rack 16, so that upon turning the thumb piece 20, 10 the rack is slowly moved along the guide 17, so as to adjust the axis of the gem to various angles with respect to the polishing surface.

It is desirable that the gem be arranged so that the center of its girdle coincide with 15 the center of the arc of the arcuate rack and arcuate guide. This can be accomplished by operating the nut 13, in order to adjust the arbor 4 with the gem 3 longitudinally to the dop spindle, so that in whatever position 20 the dop spindle 7 may be, the center of the girdle of the gem will coincide with the center of the dop arc as well as lie in the axis vertical to the polishing surface about which the dop spindle 7 is rotatable, 25 as will hereinafter more clearly appear.

As illustrated in Fig. 14, the girdle of the gem 3 is shown at 21, and the center of the girdle is indicated at 22. This center 22 coincides with the center of the dop arc, 30 or the arc of the arcuate guide 17, which is indicated by the line 23. As shown in Fig. 14, one of the angular facets 24 is in position to be polished.

The supporting arm 18 is rotatable on 35 the spindle 25, the axis of rotation passing through the center of the dop arc and center of the girdle of the gem as just explained. This arm 18 carries an index 26, coöperating with a pointer 27 fixed on the 40 spindle 25, for the purpose of indicating the angle to which the spindle 25 and gem 3 are turned. The spindle 25 is carried by a polishing head 28, which, in turn, is slidably mounted upon a horizontal cylindrical 45 supporting member 29. The polishing head 28 may be oscillated about an arc upon the horizontal cylindrical member 29, through a part of a circle, in order that the polishing head may be rocked in order that the 50 stone may be lifted from the polishing lap and inspected from time to time, without difficulty. The head 28 is held in proper vertical position with the stone on the polishing surface by coming in contact with 55 a stop 30 fixed to the member 29. A clamping screw 31 is provided in the head 28 for the purpose of locking the head in any desired position. That is, the head 28, upon the clamping screw 31 being loosened, may 60 be shifted radially on the member 29 to bring the gem onto different polishing bands of the lap and then locked in any such desired position with the gem against the polishing surface. Or, also, upon loosening the lock screw 31, the head 28 may be os-

cillated, rotating the dop spindle 7 and the gem carried thereby upwardly for inspection or adjustment of the dop and the parts locked in this position by means of the set screw 31. Upon releasing the set screw 31, 70 the head 28 may be oscillated back again to bring the gem against the polishing surface and which will bring the gem back against the lap in the same position as before, so that no new adjustment is required. 75

The spindle 25 is likewise movable vertically or longitudinally along its axis in the polishing head 28, and carries at its upper end an adjustment nut 32, having a beveled face 33, coöperating with scale marks 34, 80 on the upper end of the spindle 25. A collar fitting about a recessed portion of the adjusting nut 32 has an arm 35, having a downwardly extending rack 36, operatively engaging a pinion 37, on a shaft 38 (see 85 Fig. 12) journaled in an upward extension 39 on the polishing head 28. At its other end the shaft 38 has rigidly secured thereto a toothed wheel 40. For this purpose, a pin 41 passes through a collar 42 90 surrounding an integral collar 43 on the toothed wheel 40, and the shaft 38. Pivoted about the collar 43, between the collar 42 and the toothed wheel 40 is an arm 44, carrying an adjustable weight 45 thereon. The 95 arm 44 is provided with a spring pressed pin 46 adapted to engage the teeth of the toothed wheel 40, so that as the rack 36 moves downwardly, being carried downwardly as the spindle 25 moves downwardly, as the face of the gem being polished wears away, the gear 37 is permitted to turn, thereby permitting the shaft 38 to turn. Normally the arm 44 is adjusted to such position relative to the 100 toothed wheel 40 and shaft 38 that at the commencement of the polishing operation the arm 44 extends upwardly, nearly to the vertical. Then, as the polishing proceeds, the arm swings downwardly, as illustrated 105 in Fig. 1. The weight 45 tends to rotate the toothed wheel 40, shaft 38 and gear 37, to pull the rack 36 downwardly, thereby causing the gem 3, which is ultimately carried by the spindle 25, to be pressed against 110 the polishing surface, and, as the facet of the gem is polished away, thereby increasing its area, the pressure with which it is forced against the polishing surface is increased by reason of the arm 44 swinging 115 outwardly, more near to the horizontal, so that the weight 45 acts with greater leverage. Thus, as the gem is polished, and its facet worn away, it is pressed against the polishing surface with a gradually increasing 120 pressure.

In order to indicate the polishing operation, and show that the correct grain relation of the stone is presented to the lap, there is secured to the toothed wheel 40 a 130

collar 46', having integral therewith a gear 47, which meshes with a gear 48, fixed to a stud shaft 49, which stud shaft also has fixed thereto a large gear 50, meshing with a small gear 51, on a stud shaft 52, extending through a casing 53, formed on the upper end of the projecting portion 39, and on the outside of the casing 53, the stud shaft 52 has secured thereto a pointer 54, co-operating with a dial 55, arranged on the casing 53 (see also Fig. 1), so that, as the polishing proceeds and the shaft 38 is gradually turned proportionately thereto, motion takes place through the gears 47, 48, 50 and 51 to the pointer 54, which indicates on the dial 55 the amount of polishing that has taken place. The operator may thus tell not only how rapidly the polishing of any facet is proceeding, but also when it is nearly finished.

The gear 50 also meshes with a gear 56, carried on a stud shaft 57, which shaft has fixed thereto a larger gear, meshing with a small gear 59 on a stud shaft 60, which stud shaft has secured thereto a larger gear 61, which in turn meshes with a small gear 63 on a stud shaft 64. The stud shaft 64 has fixed thereto a cam 65, arranged eccentric to the shaft 64 and operating in a slot 66 in a weight member 67 pivoted to the casing 53 at 68. The outline of the weight member 67 is shown irregular in order to accommodate and be spaced from the various gears and shafts. A cap plate 69 is attached to the back of the casing 53, to cover up the various gears just mentioned.

The purpose of the weight member 67 is to prevent too rapid approach of the gem onto the polishing surface. Thus after the gem has been put in place in the dop spindle 7, with the spindle 25 raised, and when it is desired to proceed with the polishing, the spindle 25 is permitted to drop, so that the gem is brought down against the polishing lap 1. The lowering of the spindle 25, however, causes the downward movement of the rack 36 and the rotation of the gears within the casing 53, which causes the cam 65 to very rapidly oscillate the weight 67 about its pivot 68, which, in this manner, acts as a retarding means to cause the gem to approach the polishing lap slowly, so that it will not be injured.

Rigidly secured to the adjusting nut 32, in a V-shaped groove therein, is a collar 69, carrying a downwardly-extending arm 70, having integral with its bottom a frame member 71. The collar 69 may be made in two pieces, clamped together by a screw 72 (see Figs. 1 and 3). Pivoted in the frame piece 71 is a lever 73 having an outer end 74 and an inner end 75 normally pulled downwardly by spring 76 (see Figs. 8 and 9). The end 75 may be held in an upper position by means of a catch 77 on a trip-

ping lever 78, pivoted to the frame piece 71, at 79. The trip lever 78 is made in two pieces, the lower piece 80 comprising a foot which hangs down in close proximity to the polishing surface of the lap, which may be adjusted with respect to the upper part of the lever by means of a set screw 81. When the foot 80 engages the rotating lap, as will more fully be hereinafter explained, the catch 77 slips from beneath the nut 75, thereby permitting the spring 76 to act upon pivot arm 73, causing its end 74 to move upwardly and engage an insulating contact arm 82, carried upon, but insulated from the stop 30, so as to close an electric circuit, as will be more fully described hereinafter. The trip lever 78 is also provided with an upwardly extending catch 83, adapted to engage the underneath side of one end 84 of a lever 85, pivoted in the frame piece 71 by 85 pivot 86 (see Fig. 4). Pivoted to the lever 85, near the pivot 86, is a link 87, sliding through a frame piece 88 and carrying at its upper end a roller 89 engaging the underneath side of a flange cup 90, in which is arranged a coil spring 91, one end of which abuts against the bottom of the cup 90, and the other end of which abuts against the underneath side of the adjusting nut 32, so as to tend to separate these two. When the trip lever 78 is rocked sufficiently so that the catch 83 slips off of the end 84 of the lever 85, allowing the lever 85 to drop downwardly together with the link 87 and roller 89, then the cup member 90 is permitted to 100 drop downwardly upon a collar 92, so that then the spring acts as if directly upon the collar 92 on the polishing head 28 and causes the adjusting nut 32 to be raised relatively to the head 28. The raising of the nut 32 relative to the head 28 causes the spindle 25, upon which it is screw-threaded, to be raised and with it the arm 18, dop spindle 7 and gem 3, so that when the trip lever 78 is swung sufficiently to slip off of the end 84, the spring 91 acts to raise the gem and withdraw it from the polishing surface. The collar 92 is recessed as at 93 (see Fig. 5) to form guideways, to accommodate downwardly-extending guide members 95 carried integral with the adjusting nut 32 (see also Fig. 6).

96 represents a suitable stand, carrying a spindle 97 adjustable therein by means of a thumb screw 98; and carried upon the spindle 97 is a horizontal arm 99 to which is secured an electric motor 100. The motor 100 is adapted to drive a worm 101, meshing with a worm gear 102, on a shaft 103, which shaft carries a suitable cam (not shown) operating a link 104, the outer end of the link 104 being pivotally connected to the horizontal cylindrical member 29 at 105 (see Figs. 1 and 2), so that when the motor 100 is energized, it drives the worm 101, which 130

in turn drives the gear 102, which in turn reciprocates the link 104, which in turn reciprocates the horizontal cylindrical member 29, causing it to slide back and forth on the arm 99, and reciprocates the gem radially on the polishing lap. The motor 100 is so connected that when the end 74 is thrown upwardly by the spring 76 to contact with the contact member 82, as previously explained, the motor is energized and the reciprocation of the member 29 together with the polishing head 28 and the gem carried thereby is started.

The levers 73 and 85, together with adjacent parts, are covered by means of a casing 106, which casing, however, is provided with a slot 107, through which extends a handle 108, which handle is rigidly secured to the lever 85 (see Fig. 4).

When the handle 108 is lifted, the trip lever 78 swings in such manner that the catches 77 and 83 swing beneath the outer ends 75 and 84 respectively. The foot of the trip lever 78 has two portions struck on arcs of different radii from the point 79 about which the trip lever 78 is pivoted. The first portion 109 is struck about the greater radius while the second portion 110 is struck about the lesser radius.

In operation the gem is suitably attached to the arbor 4, which is then placed in the spindle 5 and dop spindle 7. In order that the center of the girdle may be placed coincident with the center of the dop arc lying in the axis of the spindle 25, a pointer 111 is provided (see Fig. 1) carried upon an arm 112, which may be oscillated in bearings 113 carried on the dop spindle 7. The arm 112 carries a thumb piece 114, by means of which the arm 112 may be oscillated, so that the pointer 111 is brought closely adjacent the gem 3. The gem is then adjusted to bring the girdle opposite the pointer which will place the center of the girdle coincident with the center of the dop arc. Then the polishing head 28 is slid along the cylindrical member 29 until the gem is brought over the desired polishing band on the lap 1, after which the head 28 is locked to the member 29 by means of thumbscrew 31. Then the spindle 25 is permitted to descend, the descent being retarded by means of the oscillating weight member 67, as previously explained. When the gem 3 has descended into contact with the polishing lap 1, and the lap is rotated, the polishing proceeds. As the facet of the gem is polished away, the pointer 111 indicates not only how fast the polishing operation is proceeding, but how far it has proceeded. The foot piece 80 is adjusted relative to the rest of the trip lever 78, so that when the polishing is started it is a slight distance above the polishing surface. The collar 69, arm 70, frame piece 71 and parts carried thereby are adjustable rota-

tably about the adjusting nut 32 and spindle 25, so that the foot piece 80 may be brought into the path of the gem on the polishing lap.

It is desirable that when the polishing of the facet has been nearly completed to reciprocate the gem radially over the polishing lap for a short time, in order to polish out any streaks which may have been produced in the facet. When the facet has been polished away to the point where it is desired, this reciprocation takes place, the forward part 109 of the foot 80 engages the surface of the lap, so that the rotation of the lap quickly rocks the trip lever, causing the catch 77 to slip off of the end 75, permitting the arm 74 to move upwardly and engage the electrical contact member 82 and close the electric circuit to energize the motor 100, which thereupon causes reciprocation of member 29, polishing head 28, and consequently reciprocation of the gem 3 radially over the polishing surface. This movement of the trip lever 78, however, is not sufficient to cause the catch 83 to slip off of the end 84 of lever 85. When, however, the polishing has proceeded to the desired extent and it is desired that the polishing operation cease and the gem be withdrawn from the polishing lap, the rear of the foot 110, which is at a slightly greater distance from the polishing surface than the part 109, comes into contact with the polishing surface, by reason of the gradual downward movement of the gem and its carrying spindle 25, and arm 70, and frame piece 71 carried thereby, so that then the trip lever 78 is given a further swing and the catch 83 swings off of the end 84, permitting the lever 85 to drop down, carrying down with it the link 87 and roller 89 and permitting the spring 91 to force cup 90 against the collar 92, and when the spring 91 causes the cup 90 to engage the collar 92, since it can force the cup 90 no farther downwardly, it forces the adjusting nut 32 upwardly, carrying with it the spindle 25 and gem 3, so that the gem 3 is quickly withdrawn from the polishing surface and the polishing operation stopped.

When it is desired to reset the apparatus, the handle 108 (see Figs. 2, 3 and 4) is taken hold of and raised, carrying with it the lever 85, and also the lever 73, by reason of the lever 73 having an arm 115 which engages over the top of the lever 85, so that as the lever 85 is raised it likewise raises the end 75 of the lever 73. The trip lever 78 then swings back to normal position, causing the catches 77, 83, to swing beneath the ends 75 and 84 and hold the levers 73 and 85 in position for a new operation.

From the above it will be seen that the pointer 111 acts as a setting indicator for indicating the position of the stone longitudinally of the axis of the arbor 4 and dop

spindle 7 and the thumb nut 13 acts as means for adjusting the arbor longitudinally with respect to its axis to bring the stone into proper relationship with the setting indicator, so that the center of the girdle of the stone or the geometric center of the gem is coincident with the center of the dop arc, and likewise the vertical axis about which the dop head, or dop 7, is rotatable, namely 10 the axis of the spindle 25.

It will also be noted that the weight 45 may be adjusted to various positions along the arm 44, so that the pressure with which the stone is pressed against the lap may be 15 adjusted at various stages of the polishing operation.

It will be seen that the stone carrying means, including the dop spindle 7 and head or frame 28, is pivoted to rock on the longitudinal cylindrical arm 29 in such a manner 20 that it is pivoted about an axis extending substantially parallel to the polishing face of the lap and so that the carrying means holds the stone against the lap at one side 25 of the plane drawn through said axis and at right angles to the polishing surface, whereby the stone may be lifted from the lap without stopping the polishing operation or affecting the adjustment of the stone 30 with respect to the lap when the head is again replaced.

The stand 96 and arm 99 act as a suitable frame for carrying the various parts as above described. When the head 28 is 35 thrown into position with the spindle 25, with its axis at right angles to the polishing surface, it may be locked in this position by means of the screw 31, with the stone against the lap. It will be seen further that the 40 parts which move downwardly as the polishing proceeds may be said to consist of a three-part spindle, comprising the dop spindle 7, the spindle proper 25, and the adjusting nut 32, each of these parts being adjustable one with respect to the other, and means carried on the first part or dop spindle 7 for carrying the stone to be ground in engagement with the polishing surface of the lap, namely the arbor 4, and means for adjusting this carrying part or arbor 4, comprising the nut 13, and means for adjusting the third part 32 with respect to the second part 25, comprising the screw-threaded portion of the nut 32, and that the index 34 indicates the amount of adjustment between the parts 25 and 32.

The trip member or trigger 78 is preferably arranged to track in the path which the gem takes on the lap. It may, therefore, 60 be termed a tracker carried by the spindle 25, in the path of the gem on the lap and arranged to engage the lap to be rocked thereby, at a predetermined stage of the polishing operation, whereupon, at one stage it sets into operation the motor

to reciprocate the gem and at another stage sets into operation the spring 91 to withdraw the gem from the polishing surface and discontinue the polishing operation. This withdrawing means acts as a depth 70 gage for automatically determining the depth to which the polishing off of the facet is carried. The arm 18, carrying the parts 15 and 16 and dop spindle 7 may be termed a polishing head carried by the spindle 25 and arranged to hold the gem 3 in contact with the lap. It will be seen that by adjusting the adjusting nut 32, which acts as a micrometer screw carrying the trigger 78 with its foot 80, the trigger 78, 80, 85 may be adjusted longitudinally of the spindle 25 relative to the position of the gem to the lap, in order that it will operate to trip and stop the polishing operation when the facet has been polished to its desired extent. Prior to this tripping, the levers 73 and 85, held up by the catches 77 and 83, act as locking means for locking the resilient spring in compressed condition ready to act to withdraw the gem from the lap when released. 90

Although I have described my improvements as embodied in a particular machine, it will be understood that many changes and modifications may well be made without departing from the spirit and scope of my invention in its broader aspects. Accordingly, I do not desire to be limited by the details shown and described, except as clearly specified in the appended claims. 95

What I claim as new and desire to secure by Letters Patent is:—

1. In an apparatus of the class described, the combination of a suitable frame, a carrying-head, a gem-holding arbor carried by the carrying-head, a setting-indicator for indicating the position of the stone longitudinally of the axis of the arbor and means for adjusting the arbor longitudinally with respect to its axis to bring the stone into proper relationship with the setting-indicator. 105

2. In an apparatus of the class described, the combination of a suitable frame, a polishing lap, a dop rotatable about an axis perpendicular to the lap and adjustable over an arc angularly with respect to the lap, a gem-holding arbor carried by the dop, a setting-indicator for indicating the position of the stone longitudinally of the axis of the arbor, and means for adjusting the arbor longitudinally with respect to its axis to bring the stone into proper relationship with the setting-indicator. 115

3. In an apparatus of the class described, the combination of a suitable frame, a dop, a gem-holding arbor carried by the dop, an arcuate guide for adjusting the dop and arbor angularly to polish different facets on the stone, a setting-indicator for indi- 120 125

cating the center of the arc of said arcuate guide and means for adjusting the arbor longitudinally of its axis to bring the girdle of the stone in line with said pointer whereby 5 the center of the arc of the arcuate guide may be in the center of the girdle of the stone.

4. In an apparatus of the class described, the combination of a suitable frame, a polishing lap, a dop rotatable about an axis perpendicular to the lap and adjustable over an arc angularly with respect to the lap, a gem-holding arbor carried by the dop, a setting-indicator for indicating the center 10 of the arc and means for adjusting the arbor longitudinally of its axis to bring the girdle of the stone in line with said pointer whereby the center of the arc may be in the center of the girdle of the stone, the center 15 of said arc also lying in the vertical axis about which the dop is rotatable.

5. In an apparatus of the class described, the combination of a moving polishing lap, a supporting member, and a frame extending 20 horizontally over the lap and carrying the stone to be ground against the polishing surface of the lap, said frame being pivoted to rock about an axis substantially parallel to the polishing surface of the lap, 25 whereby upon rotation of said frame the stone may be withdrawn from the lap for inspection, and means for sustaining the frame in its rotated position with the stone withdrawn from the lap.

30 6. In an apparatus of the class described, the combination of a polishing lap, a suitable frame, an arcuate guide vertically movable with respect to the frame and lap and adapted to be rotated in a plane parallel to 35 the lap, a dop carried by and adjustable along said arcuate guide, a gem-holding arbor carried by the dop, a setting indicator and means for moving and adjusting the gem-holding arbor relatively to the setting 40 indicator to bring the stone into any desired position with respect to the center of the arc of the arcuate guide, means for withdrawing the dop from the lap when the gem 45 has been ground to a predetermined extent 50 and means for adjusting the extent to which the stone may be ground before such withdrawal.

7. In an apparatus of the class described, the combination of a polishing lap, a suitable frame, means carried by the frame for 55 feeding the stone to be ground against the lap, said means embracing a train of gears operated by the movement of the stone toward the lap and a body adapted to be reciprocated by said gears, whereby the inertia of said body causes a slow approach of the stone toward the lap before the stone engages the lap.

8. In an apparatus of the class described, 60 the combination of a polishing lap, a suit-

able frame, means carried by the frame for feeding the stone to be ground against the lap, said means embracing means for causing the stone to be pressed against the lap with increasing pressure as the grinding 70 proceeds, a train of gears operated by the movement of the stone toward the lap and a body adapted to be reciprocated by said gears, whereby the inertia of said body causes a slow approach of the stone toward 75 the lap before the stone engages the lap.

9. In a machine of the class described, the combination of a polishing lap, means for holding the stone in engagement with the lap to be polished, means for causing the 80 stone to be pressed against the lap with a pressure varying as the grinding or polishing proceeds and means whereby said pressure may be adjusted at various stages of the operation.

85 10. In an apparatus of the class described, the combination of a polishing lap, a suitable frame, means carried by the frame for feeding the stone to be ground against the lap, a train of gears operated by the movement of the stone toward the lap and a pointer operated by said gears and a scale coöoperating with said pointer whereby the progress of the grinding operation is indicated.

90 11. In an apparatus of the class described, the combination of a suitable frame, a polishing lap, a dop rotatable about an axis perpendicular to the lap and adjustable over an arc angularly with respect to the lap, a 100 gem-holding arbor carried by the dop and adjustable over the arc with the dop and means for adjusting said arbor with the gem along the axis of the arbor irrespective of its angular position with respect to the lap. 105

110 12. In an apparatus of the class described, the combination of a rotary polishing lap, an arm extending over said lap, means for carrying the stone against the lap to polish the stone, a frame carrying said carrying means, said frame being pivoted on said arm about an axis extending substantially parallel to the polishing face of the lap, the carrying means holding the stone against the lap at one side of a plane drawn through 115 said axis and at right angles to the polishing surface, whereby the stone may be lifted from the lap without stopping the apparatus or affecting the adjustment of the stone with respect to the lap.

120 13. In an apparatus of the class described, the combination of a moving polishing lap, a support, a frame extending horizontally over the lap and carrying the stone to be ground against the polishing surface of the 125 lap, said frame being pivoted to rock about an axis substantially parallel to the polishing face of the lap, the stone being held against the lap at one side of the plane drawn through said axis and at right angles 130

- to the polishing surface, whereby the stone may be withdrawn from the lap for inspection without affecting the adjustment of the stone with respect to said frame.
14. In an apparatus of the class described, the combination of a moving polishing lap, a support, a frame extending over the lap and carrying the stone to be ground against the polishing surface of the lap, means for causing a slow approach of the stone toward the lap, means for withdrawing the stone from the lap when it has been ground or polished to a predetermined extent, said frame being pivoted to rock about an axis substantially parallel to the polishing face of the lap, the stone being held against the lap at one side of the plane drawn through said axis and at right angles to the polishing surface whereby the stone may be withdrawn from the lap for inspection without affecting the adjustment of the stone with respect to said frame. 75
15. In an apparatus of the class described, the combination of a moving polishing lap, a frame extending over the lap, means movable relatively to the said frame and carrying the stone in engagement with the lap to effect the polishing or grinding of the stone, means for causing a slow approach of the stone toward the lap, means for withdrawing the stone from the lap when it has been ground or polished to a predetermined extent and means whereby the operator may at will withdraw the stone and its carrying means from the lap to inspect the stone and replace the same without affecting the adjustment of the stone with respect to the frame. 90
16. In an apparatus of the class described, the combination of a moving polishing lap, a support, and a frame extending horizontally over the lap and carrying the stone to be ground against the polishing surface of the lap, said frame being pivoted to rock about an axis substantially parallel to the polishing surface of the lap, whereby upon rotation of said frame the stone may be withdrawn from the lap for inspection. 95
17. In an apparatus of the class described, the combination of a polishing lap, a frame, a three-part spindle, movable in the frame toward and from the lap, each of said parts being adjustable one with respect to another, means carried by one part of the spindle for carrying the stone to be ground in engagement with the polishing surface of the lap, means for adjusting said carrying part with respect to the second part of the spindle, means for adjusting the third part with respect to the second part of the spindle, an indicating device for indicating the extent to which the grinding has progressed, engaging the third part of the spindle. 110
18. A gem-polishing machine, comprising a polishing lap, a spindle at right angles to the polishing surface of the lap, an arcuate guide carried by the spindle and a dop head adjustable upon said arcuate guide and provided with gem-holding means adapted to hold the geometric center of the gem or center of the girdle at the center of the arcuate guide and in the axial line of the spindle at various positions of the dop head upon the arcuate guide while different facets of the gem are being polished. 115
19. A gem-polishing machine, comprising a polishing lap, a spindle at right angles to the polishing surface of the lap, an arcuate guide carried by the spindle and a dop head adjustable upon said arcuate guide and provided with gem-holding means adapted to hold the geometric center of the gem or the center of the girdle in the axial line of the spindle at various positions of the dop head upon the arcuate guide while different facets of the gem are being polished. 120
20. A gem polishing machine having in combination a polishing lap, a gem holder for holding the gem in contact with the lap, means for reciprocating the gem-holding means and gem over the lap during the polishing when the gem has been polished to a predetermined extent, means for discontinuing the polishing when the gem has been polished to a predetermined extent, and a single trigger member for causing the actuation of both of said withdrawing means and reciprocating means. 125
21. A gem polishing machine having in combination a polishing lap, a gem holder for holding the gem in contact with the lap, means for reciprocating the gem-holding means and gem over the lap during the polishing when the gem has been polished to a predetermined extent, means for withdrawing the gem from the lap when the gem has been polished to a predetermined extent, and a trigger member for causing the actuation of both of said withdrawing means and reciprocating means by the engagement of the trigger member with the lap. 130
22. A gem polishing machine having in combination, a polishing lap, a gem-holding means comprising an arcuate guide and a gem-holding dop adjustable along said guide to present different facets of the gem to the lap, and a worm and coöperating rack for adjusting the gem-holding dop along said arcuate guide. 135
23. A gem polishing machine having in combination, a polishing lap, a gem-holding means comprising an arcuate guide and a gem-holding dop adjustable along said guide to present different facets of the gem to the lap, and a screw device for adjusting the gem-holding dop along said arcuate guide. 140
24. In an apparatus of the class described, the combination of a polishing lap, a frame, 130

a three-part spindle, movable in the frame toward and from the lap, each of said parts being adjustable one with respect to another in series relation, means carried by one part 5 of the spindle for carrying the stone to be ground in engagement with the polishing surface of the lap, means for adjusting said carrying part with respect to the second part of the spindle, means for adjusting the 10 third part with respect to the second part of the spindle, a tripping mechanism engaging the third part of the spindle to be operated by the movement thereof, whereby, when said third part has moved a predetermined distance toward the lap, said tripping mechanism is operated to withdraw the stone from the lap.

25. In an apparatus of the class described, the combination of a polishing lap, a frame, 20 a three-part spindle, movable in the frame toward and from the lap, each of said parts being adjustable one with respect to another in series relation, means carried by one part of the spindle for carrying the stone to be 25 ground in engagement with the polishing surface of the lap, means for adjusting said carrying part with respect to the second part of the spindle, means for adjusting the third part with respect to the second part 30 of the spindle, and an indicating device for indicating the extent to which the grinding has progressed, engaging the third part of the spindle.

26. In an apparatus of the class described, 35 the combination of a polishing lap, a frame, a three-part spindle, movable in the frame toward and from the lap, each of said parts being adjustable one with respect to another in series relation, means carried by one part 40 of the spindle for carrying the stone to be ground in engagement with the polishing surface of the lap, means for adjusting said carrying part with respect to the second part of the spindle, means for adjusting the 45 third part with respect to the second part of the spindle, an indicating device for indicating the extent to which the grinding has progressed, engaging the third part of the spindle, and means for adjusting said 50 first-mentioned part of the spindle up and down relatively to said second-mentioned part to adjust the stone with respect to the lap without affecting the reading of said indicating device.

55. 27. In an apparatus of the class described, the combination of an arcuate guide, polishing means, a gem-holding dop adjustable on said guide to present various facets of the gem to the polishing means, a gem-holding 60 arbor carried by the dop, and a screw device for adjusting the gem-holding arbor axially of the dop.

28. In an apparatus of the class described, 65 the combination of an arcuate guide, polishing means, a gem-holding dop adjustable

on said guide to present various facets of the gem to the polishing means, a gem-holding arbor carried by the dop, a screw device for adjusting the gem-holding arbor axially of the dop, and means for adjusting the gem-holding arbor rotatively with respect to its axis.

29. A gem polishing machine, comprising a polishing lap, a spindle at right angles to the polishing surface of the lap, an arcuate guide carried by the spindle and a dop head adjustable upon said arcuate guide and provided with gem-holding means adapted to hold the center of the girdle of the gem at the center of the arcuate guide 70 and in the axial line of the spindle at various positions of the dop head upon the arcuate guide while different facets of the gem are being polished.

30. A gem polishing machine, comprising a polishing lap, a spindle at right angles to the polishing surface of the lap, an arcuate guide carried by the spindle and a dop head adjustable upon said arcuate guide and provided with gem-holding means adapted 80 to hold the center of the girdle of the gem at the center of the arcuate guide and in the axial line of the spindle at various positions of the dop head upon the arcuate guide while different facets of the gem are 85 being polished and driving means for rotating said spindle to rotate the gem on the polishing lap.

31. A gem polishing machine, comprising a polishing lap, a spindle at right angles to the polishing surface of the lap, an arcuate guide carried by the spindle and a dop head adjustable upon said arcuate guide and provided with gem-holding means adapted to hold the center of the girdle of the gem 100 at the center of the arcuate guide and in the axial line of the spindle at various positions of the dop head upon the arcuate guide while different facets of the gem are 105 being polished.

32. A gem polishing machine, comprising a polishing lap, a spindle at right angles to the polishing surface of the lap, an arcuate guide carried by the spindle and a dop head adjustable upon said arcuate guide and provided with gem-holding means adapted to 110 hold the center of the girdle of the gem in the axial line of the spindle at various positions of the dop head upon the arcuate guide while different facets of the gem are being polished and driving means adapted to rotate the gem while in contact with the polishing surface about an axis at right angles to the polishing surface.

33. A gem polishing machine having in combination a rotary polishing lap, a spindle having its axis arranged at right angles to the polishing surface of the lap, an arcuate guide carried by the spindle, having its center in the axis of said spindle, a dop or gem carrying head adjustably mounted on 125

5 said guide and adapted to carry the gem with the center of its girdle at the center of the arcuate guide, at various positions of the 10 dop head on the guide, means whereby the 5 gem may be rotated about an axis at right angles to the polishing surface, and means whereby the gem may be moved laterally over the polishing surface of the lap to change its position from one polishing band 15 to another.

10 34. In an apparatus of the class described, a polishing lap, means for holding a gem against the polishing surface of the lap to polish the gem, said means including an ar- 15 bbor having a recessed end containing an adhesive for securing the gem to the arbor, and said arbor being provided with a hole extending into the recess through which hole a pin or tool may be operated to dislodge 20 the gem from the arbor.

25 35. In an apparatus of the class described, a polishing lap, means for holding a gem in engagement with the polishing surface of the lap to polish the gem, said means having an arbor having a recessed end containing an adhesive for securing the gem to the ar- 30 bbor and means whereby the cement and gem may be forced out of the recessed end of the arbor.

35 36. In an apparatus of the class described, a polishing lap, means for holding a gem in engagement with the polishing surface of the lap to polish the gem, said means comprising a suitable frame, a dop carried thereby and a gem holding arbor carried by the dop, the dop and arbor having means for registering one with respect to the other, whereby the arbor may always be inserted in the dop in one rotative position with respect thereto.

40 37. In an apparatus of the class described, a polishing lap, means for holding a gem in engagement with the polishing surface of the lap to polish the gem, means for pro- 45 gressively increasing the pressure with which the stone is applied to the polishing surface as the surface area of the facet of the stone being polished is increased, and means for adjusting or changing the said 50 pressure during such range of variable pressure.

55 38. In an apparatus of the class described, the combination of a suitable frame, a pol- 60 ishing lap, a carrying head, a gem holding arbor carried by the carrying head, an ad- 65 justable setting indicator and means for moving and adjusting the gem holding arbor toward the lap relatively to the setting indicator.

70 39. In an apparatus of the class described, the combination of a polishing lap, a spin- 75 dle having its axis perpendicular to the lap and rotatable in a plane parallel thereto, an arcuate guide carried by said spindle, a car- 80 rying head carried by and adjustable along

85 said guide, a stone containing arbor carried by said carrying head, a setting indicator, and means for adjusting the position of the stone and arbor so as to bring the axial line of the spindle substantially in the center of the 90 face of the stone being ground, irrespective of the position of the carrying head in the arcuate guide.

95 40. In an apparatus of the class described, the combination of a suitable polishing lap, a carrying head, a gem holding arbor carried by the carrying head, a setting indicator and means for moving and adjusting the gem holding arbor relatively to the set- 100 ting indicator toward the lap.

105 41. In an apparatus of the class described, the combination of a polishing lap, a dop- carrying head, a gem holding arbor carried by the carrying head, means for withdrawing the head and stone from the lap when the 110 stone has been ground to a predetermined extent, means for adjusting the position of the head at which said withdrawing takes place, a setting indicator, and means for moving the gem holding arbor toward the lap rela- 115 tively to the setting indicator to bring the gem into proper grinding position.

120 42. In an apparatus of the class described, the combination of a polishing lap, a suitable frame, an arcuate guide vertically movable with respect to the frame and lap and adapted to be rotated in a plane parallel to the lap, a dop carrying head carried by and adjustable along said arcuate guide, a gem holding arbor carried by the carrying head, 125 a setting indicator and means for moving and adjusting the gem holding arbor relatively to the setting indicator so as to bring the axial line of said guide substantially in the center of the face of the stone being 130 ground, irrespective of the position of the carrying head in the arcuate guide.

135 43. In an apparatus of the class described, the combination of a polishing lap, a spindle having its axis perpendicular to the lap and 140 rotatable in a plane parallel thereto, an arcuate guide carried by said spindle, a carrying head carried by and adjustable along said guide, a setting indicator, a stone containing arbor carried by said carrying head, 145 means for withdrawing the spindle and carrying head from the lap when the stone has been ground to a predetermined extent, means for adjusting the position of the spindle at which said withdrawing takes place 150 and means for adjusting the position of the stone and arbor so as to bring the axial line of the spindle substantially in the center of the face of the stone being ground, irrespec- 155 tive of the position of the carrying head in the arcuate guide.

160 44. In an apparatus of the class described, the combination of a polishing lap, a suitable frame, an arcuate guide vertically movable with respect to the frame and lap and 165

adapted to be rotated in a plane parallel to the lap, a dop carrying head carried by and adjustable along said arcuate guide, a gem holding arbor carried by the carrying head, 5 a setting indicator and means for moving and adjusting the gem holding arbor toward the lap relatively to the setting indicator and means for withdrawing the dop carrying head from the lap when the gem has 10 been ground to a predetermined extent, and means for adjusting the extent to which the stone may be ground before such withdrawal, each of said adjusting means being operable independently of the others.

45. In an apparatus of the class described, the combination of a polishing lap, a frame, a main spindle slidably mounted in the frame to move toward the lap and carrying the stone to be polished in engagement with the lap, means for forcing the spindle toward the lap, an indicating device connected therewith for indicating the movement of the spindle and stone with respect to the lap, and means opposing said forcing means, tending to force the spindle away from said lap during the polishing.

CLYDE J. COLEMAN.
